UNITED STATES PATENT OFFICE.

ANDREW J. SANFORD, OF NEWARK, OHIO, ASSIGNOR TO A. H. HEISEY & CO., OF NEWARK, OHIO.

KNOB-GRINDING MACHINE.

1,289,924.

Specification of Letters Patent. Patented Dec. 31, 1918.

Application filed September 12, 1914. Serial No. 861,418.

To all whom it may concern:

Be it known that I, ANDREW J. SANFORD, a citizen of the United States, and resident of Newark, in the county of Licking and 5 State of Ohio, have invented a new and useful Improvement in Knob-Grinding Machines; and I do hereby declare the following to be a full, clear, and exact description thereof.

10 My invention relates to knob grinding machine or to a machine for grinding and finishing a spherical face on the top of a knob, usually the knob of a bottle or jar, but it is equally adapted for finishing the 15 ends of door knobs and the like made of glass. The invention also contemplates forming not only a convex spherical face on objects of this character, but also forming a concave spherical face on glass articles where such form of face is desired. A 20 further object of the invention is to provide means for operating upon a plurality of objects simultaneously. A further object is to provide such means that by the operation 25 thereof spherical faces of great accuracy and uniformity may be formed on the several objects.

With these and other objects in view as will appear from the following description, 30 the invention consists in the construction and arrangement of parts, a preferred embodiment of which is illustrated in the accompanying drawing, in which Figure 1 is a front elevation of so much of the machine 35 as is necessary to illustrate the arrangement of the parts; Fig. 2 is a section on the line 2—2, Fig. 1, looking in the direction of the arrow; Fig. 3 is a vertical sectional view of one of the knob grinding chucks and the 40 operating parts therefor; Fig. 4 is a horizontal sectional view on the line 4—4, Fig. 2; and Fig. 5 is a view partly in section of a modified form of the invention for grinding a concave spherical surface.

45 In the embodiment of the invention illustrated in Figs. 1 to 4 inclusive, 1—1 indicate the lateral standards of the machine, in the lower part of which is journaled shaft 2 driven by a belt 3 on the fast and loose 50 pulleys 4 and 5 respectively. On this shaft are fixed the grinding wheels 6, here shown four in number. The face of each wheel as shown in Fig. 1 is concave as at 7, in order to grind a convex spherical face on 55 the article to be finished. Above each wheel

is mounted a chuck head 7, each of which is provided with a cylindrical boss or socket 8 within which the outer end of a rocking sleeve or shaft 9 is fixed by a set screw 10. This hollow rock shaft or sleeve 9 is journaled in bearings 11—11 formed on an adjustable framework 12. This framework 12 is adjustable vertically in a bracket 13 secured to a cross bar 14 at the front of the main frame of the machine (see Fig. 2). 65 As shown in Fig. 4, the frame 12 has beveled side edges 15 held in dovetailed guide-ways 16—16', the latter of which is detachable as by bolt 17 to facilitate the mounting of the frame in the guide-ways. The adjustable frame 12 is provided with an adjusting screw 18 threaded through a lug 19 of the stationary bracket 13 and the upper edge of the screw 18 is provided with a hand wheel 20 by which the adjustable 70 frame may be adjusted up and down to regulate the position of the chuck-head 7 with respect to the grinding wheel 6, so that articles of different size may be ground to the proper curvature. 80

In order that a spherical surface may be ground on the knob or other article by means of the grinding wheel 6, it is necessary that the chuck-head be rocked from side to side with respect to the grinding wheel, and at the same time that the knob or other article be revolved in a plane at right angles to its axis. With these ends in view, the chuck-head shaft 9 has attached thereto a rocking arm 21, the outer end of which is connected by a rod 22 and an eccentric strap 23 with an eccentric 24 fixed to a shaft 25 journaled in a bearing sleeve 26 at the upper end of the adjustable frame or bracket 12. The rear end of the shaft 25 90 is provided with a gear 27 meshed in with a gear 28, slidably fixed on a vertical shaft 29. This shaft 29 is also provided with a beveled driving gear 30, which is splined to the shaft and is slidably mounted thereon, and is held in mesh with a gear 31 on the shaft 32 by means of a supporting sleeve 33 carried by the frame arm 34. The shaft 32 is journaled in bearings 35 on the frame arm 34 and has at its forward end a worm gear 36 driven by a worm 37 fixed to a transverse shaft 38 journaled in bearings 39 at the top of the machine frame. The shaft 38 is driven by a pulley 40 connected by belt 41 with a pulley 42 fixed to the main guide 100 105 110

shaft 2. Thus it will be seen that as the machine operates, the entire chuck-head 7 will be rocked transversely of the adjacent grinding wheel 6. In order to produce a true spherical surface on the article ground, it is necessary to provide the gear 28 with one or two more teeth than the gear 27 in order to vary the rocking movement of the chuck-head slightly with reference to the 10 rotary movement of the chuck as hereafter described; otherwise, the cut would be somewhat conical. In order to give the required rotary movement to the chuck and referring particularly to Fig. 3, it will be found that 15 the chuck-head 7 is provided with a bearing sleeve 43, having an integral ball race 44 at its lower end and an adjustable ball race 45 threaded to its upper end, said adjustable ball race is fixed in position on the 20 sleeve 43 by means of a set ring 46. Between the ball races 44 and 45 are interposed bearing balls running in ball races 48 and 49 respectively formed in the opposite end of the chuck-head 7. Threaded upon 25 the chuck sleeve 43 is a gear ring 50, held in adjusted position on the sleeve by a set ring 51. This gear ring meshes with a beveled gear 52 fixed upon a shaft 53 journaled within the rocking sleeve or shaft 9. The 30 outer end of the shaft 53 is provided with a beveled gear wheel 54, which in turn meshes with a beveled gear 55 fixed upon the vertical shaft 29. It will be seen, therefore, that as the machine operates, the chuck 35 sleeve 51 will be constantly rotating.

In order to hold the work firmly within the chuck-head, a chuck 56 is provided, on the outer periphery of which are formed locking ribs 57 which as shown in Fig. 4, engage 40 between corresponding locking ribs 58 formed on the inner walls of the chuck sleeve 43. The chuck 56 is provided at its lower end with a socket or work-receiving recess 59, within which is mounted a plurality of 45 clamping arms 60, the inner ends of which are recessed at 61 to engage the adjusting disk 62 fixed to the lower end of a spring held rod 63. Upon the upper end of the rod 63 is fixed a sleeve 64 forming an abutment 50 for a coiled spring 65, the opposite end of which rests upon an angular shoulder 66 in the bore 67 of the chuck 56. The spring 65 tends normally to withdraw the rod 63 within 55 the bore 67 of the chuck. Surrounding the lower end or opening of the work-receiving and clamping recess 59 of the chuck 56, may be mounted a stop ring 68, which may be composed of rubber or other comparatively soft material. It will be seen from an 60 inspection of Fig. 3, that the bore or diameter of the work-receiving recess 60 of the chuck 56 is so small that when the clamping fingers 60 are drawn within this recess they tend to collapse. The work, which in Fig. 3 65 is represented as a glass knob 69, is provided

with a flange or bead 70 which may be engaged by the hook shaped outer ends 71 of the clamping fingers 60, so that under the pull of the spring 65 of the chuck, the clamping fingers 60 together with the work held 70 thereby will be drawn within the work-receiving recess 59, and the contracted diameter of said recess will cause the clamping fingers to firmly clamp and hold the work and draw it against the cushion like rubber ring 68 at the mouth of the chuck recess 59. Thus the work is held within the chuck firmly to permit the work to undergo its rocking and turning movements during the grinding operation. For pieces of work of 80 considerably greater or less diameter than that here shown, it is merely necessary to substitute in the chuck-head a chuck having a recess of greater or less diameter as the case may be. Small variations of the diameter of the work, however, may be taken care of in the same chuck.

Should it be necessary to rough grind the work before the finishing operation, abrading sand or other material may be supplied 90 to the grinding face of the grinding wheel 6 by means of a pipe 72, Fig. 3, leading from a suitable source of such material.

When the machine is used for grinding convex spherical faces upon the work, it will 95 be noticed that the center of oscillation or rocking of the work must be above the surface being finished, or above the grinding face of the grinding wheel. When it is desired to grind a concave spherical face on the 100 work, it is necessary that the center of oscillation be below or outside the portion of the work being operated upon, and below or within the circumference of the grinding wheel. Also in grinding a concave surface, 105 the grinding face of the grinding wheel must be convex transversely instead of concave as heretofore described.

An apparatus embodying means for concave grinding is indicated in Fig. 5 in the 110 drawing. The parts of this apparatus are in many respects the same as those heretofore described except that the rocking sleeve 73 instead of lying above the circumference of the grinding wheel, lies within or below said 115 circumference. The grinding wheel 74 in this case has a convex circumference instead of a concave circumference as heretofore described. This together with the fact that the rocking sleeve 73 is below or extends along a line within the circumference of the grinding wheel, produces a concave surface in the article ground instead of a convex surface as heretofore described. The mechanism of Fig. 5 is, of course, provided with the same 120 rocking mechanism—such as the lever 21 and rod 22—as that illustrated in connection with Figs. 1 and 3. It may also be desirable to vary the size or diameter of the concave cutting; that is to say, make the concavity 125 130

deep or shallow as the case may be. To this end the sleeve 73 is pinned or secured at 74 to a boxlike bracket 75, having a journal bearing in the bottom thereof for a shaft 77. 5 A gear 78 fixed on the inner end of the shaft 53 meshes with a gear 79 fixed to the shaft 77. Adjustably mounted on suitable guide-ways 80 and 81 of the lower bracket 75 is an upper boxlike bracket member 82 within a 10 bearing 83 of which is journaled a sleeve 84 of the chuck-head 85. In order to rotate the chuck in the chuck-head, a shaft 86 corre- 15 sponding to shaft 53, Fig. 3, is journaled in the chuck-head sleeve 84. The end of the shaft 86, which projects into upper adjust- 20 able bearing bracket 82, has fixed thereto a gear 87 which meshes with a gear 88 splined on the upper end of the shaft 77. The gear 88 is free to slide on said shaft 77, and the 25 upper bracket member has fixed thereto an arm 89 which slidably engages the shaft 77 and supports the gear 88 in adjustable position thereon. It will be seen, therefore, that the upper bearing bracket 82 may be ad- 30 justed up and down with reference to the axis of the rocking sleeve 73 so that the radius of the arc movement of the chuck-head 35 85 may be varied. This obviously in conjunction with the curvature of the circum- 40 ference of the grinding wheel 74, will vary the diameter of the concavity of the face of the article to be ground.

While I have herein described various preferred embodiments of my invention, it is 35 to be understood that the invention is not limited to the construction and arrangement of parts herein described, but may be varied in detail within the scope of the appended 45 claims.

40 **What I claim is:**

1. In a grinding machine, the combina- 45 tion with a grinding wheel having a trans- versely curved grinding face, and means for driving said wheel, of a work holder having actuating connections for rocking the work transversely of said wheel and for simulta- 50 neously revolving the work on its own axis to grind a spherical surface on the work, and means for adjusting said work holder to- 55 ward and from said grinding wheel.

2. In a grinding machine, the combination 55 with a grinding wheel, having a transversely curved grinding face and means for driv- 60 ing said wheel, of a work holder, comprising a chuck-head, a rock shaft fixed to said head, actuating connections for said rock shaft, a revoluble chuck mounted within said head, an actuating shaft mounted within said rock 65 shaft and adapted to revolve said chuck, an operating connection for rocking and re- 70 volving the work in synchronism to form a spherical face on the work.

3. In a grinding machine, the combination 75 with a plurality of grinding wheels, each having a transversely curved grinding face,

and means for operating said wheel, a work holder for each wheel, and operative connections for rocking said work holder and revolving the work on its axis, all of said operating connections being constructed and 70 arranged to operate in synchronism to form spherical faces on each piece of work simulta- 75 neously and uniformly, and means for adjusting of said work holders independently with respect to its grinding wheel to accom- 80 modate pieces of work of different size and to vary the diameter of curvature of the ground face.

4. A work holder for a grinding machine comprising a chuck-head, having a rock 80 shaft fixed thereto, a chuck sleeve rotatably mounted within said head, said sleeve having a gear attached thereto, a shaft mounted within said rock shaft, a gear carried by said second shaft and meshing with said 85 sleeve gear, a work holding chuck removably mounted within said sleeve and having interlocking means with said sleeve to cause said chuck to revolve with said sleeve, said chuck having spring actuated arms to grip 90 the work and hold the same against rotating with respect to said chuck.

5. In a grinding machine, the combina- 95 tion with a grinding-wheel having a curved grinding surface and means for driving said wheel, of a work-holder having means for rocking the work transversely of the grind- 100 ing surface of the wheel, and means for si- multaneously revolving the work on its own axis while in engagement with the wheel in order to grind a substantially spherical sur- 105 face on the work, said revolving means and said rocking means being so relatively ar- ranged as to continually vary the presenta- 110 tion of the surface to be ground to the grinding-wheel.

6. In a grinding machine, the combina- 110 tion with a grinding-wheel having a curved grinding surface and means for driving said wheel, of a work-holder for rocking the work 115 transversely of said grinding surface, and means for simultaneously revolving the work on its own axis while in engagement with said surface, said rocking and revolving means being so constructed and arranged 120 as to vary the presentation of the work to the grinding surface to produce a spherical surface on the work.

7. In a grinding machine, the combina- 120 tion with a grinding-wheel having a curved grinding surface and means for driving said wheel, of a work-holder having means for rocking the work transversely of said grind- 125 ing surface, and means for simultaneously revolving the work on its own axis, common means for operating the rocking and re- 130 volving means respectively, the connections of said common driving means with said rocking and revolving means respectively be- 135 ing so synchronized as to vary the presenta-

tion of the work to the grinding surface in a way to produce a spherical surface on the work.

8. In a grinding machine, the combination with a grinding-wheel having a curved grinding surface and means for driving said wheel, of a work-holder having means for rocking the work transversely of the grinding surface, and means for simultaneously 10 revolving the work on its own axis while in

engagement with the grinding surface, the rocking axis of the work being located on a line extending between the grinding surface of the wheel and the center of the wheel.

In testimony whereof, I the said ANDREW 15 J. SANFORD, have hereunto set my hand.

ANDREW J. SANFORD.
